US00D934795S

(12) **United States Design Patent** (10) **Patent No.:** **US D934,795 S**
(45) **Date of Patent:** **** Nov. 2, 2021**

(54) **CHARGING PAD**

(71) Applicant: **Nomad Goods, Inc.**, Santa Barbara, CA (US)

(72) Inventors: **Brian Hahn**, Santa Barbara, CA (US); **Tane Martin**, Santa Barbara, CA (US); **Tanner Walker**, Santa Barbara, CA (US); **Nicholas Walden**, Santa Barbara, CA (US); **Becky Liu**, Santa Barbara, CA (US); **Peter Ducato**, Santa Barbara, CA (US); **Ryan Thomas**, Santa Barbara, CA (US); **Mulin Yang**, Goleta, CA (US)

(73) Assignee: **Nomad Goods, Inc.**, Santa Barbara, CA (US)

(**) Term: **15 Years**

(21) Appl. No.: **29/731,607**

(22) Filed: **Apr. 16, 2020**

(51) LOC (13) Cl. **13-02**

(52) U.S. Cl.

USPC **D13/108**

(58) **Field of Classification Search**

USPC D13/103, 107, 108, 109, 110, 118, 119, D13/199; D14/251, 253, 432, 433, 434; D27/172, 183, 193, 194

CPC H01M 2220/00; H02J 50/00; H02J 15/00

(57) **CLAIM**

The ornamental design for a charging pad, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a top perspective view of a charging pad;

FIG. 2 is a bottom perspective view thereof;

FIG. 3 is a front view thereof;

FIG. 4 is a back view thereof;

FIG. 5 is a right-side view thereof;

FIG. 6 is a left-side view thereof;

FIG. 7 is a top view thereof; and,

FIG. 8 is a bottom view thereof.

The broken lines shown represent unclaimed subject matter and form no part of the claimed design.

1 Claim, 6 Drawing Sheets
